UNITED STATES PATENT OFFICE.

JOHN E. PATTON, OF CHATTANOOGA, TENNESSEE.

DINNER-BUCKET.

SPECIFICATION forming part of Letters Patent No. 259,582, dated June 13, 1882.

Application filed April 15, 1882. (No model.)

To all whom it may concern:

Be it known that I, JOHN E. PATTON, a citizen of the United States, residing at Chattanooga, in the county of Hamilton and State 5 of Tennessee, have invented certain new and useful Improvements in Dinner-Buckets; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 The present invention relates to that class of articles known as "dinner-buckets," which are chiefly designed for carrying the food of workmen. It is a well-known fact that the contents of ordinary dinner-buckets are liable 20 to be stolen, because no safeguard is provided for preventing easy access thereto.

25 The object of my invention is to provide a simple, convenient, and effective device for locking the cover of a dinner-bucket and retaining in position the customary drinking-cup, condiment-receptacles, and knife and fork belonging to a complete dinner-bucket outfit.

30 To these ends the invention consists in the construction and combination of parts which will hereinafter be more fully described, and then set forth in the claims.

35 In the drawings, Figure 1 is a perspective view of a dinner-bucket having its cover and appendages in accordance with my invention. Fig. 2 is a detached view of a divided or split hasp and the manner of fitting the drinking-cup thereon. Fig. 3 is a detail view of the auxiliary hasp for retaining the knife and fork.

40 The letter A designates a dinner-bucket of any approved construction, B the cover thereof, and C the drinking-cup, supported upon the cover.

45 At one side of the bucket is a loop, a, which receives a hook, b, on the back of a condiment-box, D. This box is generally made in two parts, and is designed to contain salt and pepper, and its cover d has a loop, d', which fits over an eye, d'', extending above the box and secured thereto.

50 A hasp or fastening device, E, has one of its ends bent so as to form an upwardly-projecting

hook, e, which fits into the aforesaid eye d'' on the condiment-box. The opposite end of the hasp terminates in an eye or loop, e', which is received by or fits onto a staple, F, on the side 55 of the bucket. The hasp is generally made of a single wire bent or twisted so as to possess a solid end part, a circular or oblong middle part, and a second split or divided end part, terminating in the hook e. This construction 60 is clearly shown in Fig. 2, and the object thereof is to permit the handle of the drinking-cup to be introduced between the two wires or members of the hasp, or removed therefrom, as may 65 be desired. The central or open portion of the hasp is large enough to encircle the cup and bears upon the cover of the bucket. The loop or eye e' of the hasp is fitted on the staple F, as already mentioned, and the eye or loop g of a second hasp or frame, G, is also fitted thereon, and a padlock, H, is then applied to the 70 staple for holding the two hasps in a locked position.

The hasp G serves as a holding-frame for the knife and fork h i, which are inserted into 75 keepers at the side of the bucket, and said hasp, as is shown in Fig. 3, has two openings which receive respectively the handles of the knife and fork. Projections m on the latter serve to prevent the withdrawal thereof; or the 80 handles may be made large enough at the bottom, so that they cannot be drawn out of the hasp.

The cover of the bucket and the various appendages above stated can be readily removed 85 by inserting the proper key into the padlock, unlocking it, and detaching the same from the staple. This having been done, the hasp G is first removed from the staple, and then the main hasp E is disengaged from the eye and 90 staple on the bucket, when access can be had to the contents of the bucket.

The drinking-cup, as heretofore stated, is disengaged from the hasp by passing its handle through the split end portion thereof. 95

Having thus described my invention, what I claim as new, and desire to secure by Letters Patent, is—

1. A dinner-bucket having a device for locking the cover and condiment-box thereof, consisting of a hasp provided with an end hook and an end loop, in combination with the

bucket-body having staples for receiving the hasp and a padlock, as and for the purpose set forth.

2. The divided or split hasp adapted to fit on the drinking-cup, in combination with the bucket having staples for receiving the hasp, as and for the purpose set forth.

3. The supplementary hasp having openings for the passage of knife and fork, in combina-

tion with main hasp and the staple and padlock on the body of the bucket, as and for the purpose set forth.

In testimony whereof I affix my signature in presence of two witnesses.

JOHN ESQUARE PATTON.
